DEVICE FOR HOLDING A FLEXIBLE LINER IN RECEPTACLES

Charles T. Heitz, 315 NE. 28th Ave.,
Portland, Oreg. 97232

Filed Nov. 25, 1968, Ser. No. 14,643

Term of patent 14 years

Int. Cl. D7—99

U.S. Cl. D49—30

FIG. 1

FIG. 2

FIG. 1 is a top plan view of a device for holding a flexible liner in receptacles, showing my new design; and FIG. 2 is a side elevation thereof.

I claim:

The ornamental design for a device for holding a flexible liner in receptacles, as shown.
